David Hathaway, of Troy, N.Y.
Assignee to Fuller, Warren & Co. of same place.
Letters Patent No. 1290, dated July 31, 1860.

The schedule referred in these Letters Patent and making part of the same.

To all whom it may concern;

Be it known that I, David Hathaway, of the City of Troy,
in the County of Rensselaer, and State of New York, have invented or produced a new
and original ornamental Design for six-plate Stoves, and I do hereby declare that
the following contains a full and exact description of the same, reference being had to
the annexed photographic drawings which make a part of this specification and in
which

Fig. 1. is the top plate,

Fig. 2. one of the two side plates,

Fig. 3. the door of a stove bearing my said design.

In this design the top plate is ornamented with the scalloped
bead-like moulding, a, arranged in an elliptical or oval form thereon, as shown in
Fig. 1. Each side plate has an undulating or wave like surface composed of upright
swelling projections, b, alternating with hollow depressions, c; and is ornamented
along its upper part by the series of gothic hanging arches, d, with pendants, e, and
standards, f, shaped and disposed as represented in Fig. 2. And the door at the front
end of the stove is ornamented with the scalloped border moulding, g, and the centre
